PACKET

Michael J. Cerino, Portland, Oreg., assignor to
 Firm Blade Razor Company, Inc., Portland,
 Oreg., a corporation of Oregon

Application September 11, 1950, Serial No. 184,180

5 Claims. (Cl. 206—45.21)

1

This invention pertains to merchandise packages, and relates particularly to the novel construction of a packet by which razor blades, needles, hair pins and other articles of manufacture may be packaged for sale and display.

It is a principal object of the present invention to provide a packet of the folder type wherein articles are disposed loosely for convenient removal out confined against displacement when the packet is closed.

Another important object of this invention is the provision of a packet constructed from a single blank and folded in such manner as to facilitate the packaging of articles therein for shipment, display and sale.

A further object of this invention is the provision of a folder-type packet which may be arranged either to confine articles of manufacture therein for shipment or to display the articles openly for convenient access.

A still further and specific object of this invention is the provision of a folder-type packet in which a plurality of razor blades may be packaged loosely for shipment and to facilitate individual removal.

These and other objects and advantages of the present invention will appear from the following detailed description taken in connection with the accompanying drawing, in which:

Figure 1 is a perspective view of a razor blade packet embodying the features of this invention and showing the same in closed position;

Figure 2 is a front view of the packet shown in Figure 1;

Figure 3 is a side view of the packet shown in Figure 2;

Figure 4 is a perspective view of the packet showing the same in open position;

Figure 5 is a sectional view of the packet illustrated in Figure 4 and showing the same supported in vertical position;

Figure 6 is a side view of the packet showing the same arranged in open position for displaying the razor blades from a horizontal support;

Figure 7 is a plan view of a blank from which the above razor blade packet is constructed; and

Figure 8 is a plan view of a blank from which a modified form of packet is constructed.

Referring to the drawing, the packet is preferably constructed from a single blank of heavy paper, cardboard, plastic, or other suitable sheet material. In the embodiments illustrated, the blank is of substantially rectangular shape. The blank is intended to be bent along the transverse dotted line 1 and preferably along the

2

dotted lines 2 and 3. A single line may be used in place of the spaced lines 2 and 3, although the latter construction is preferred. Similarly, a pair of spaced lines may be substituted for the single bending line 1. In any event, the lines may, if desired, constitute score lines impressed in the blank by means well-known in the art. The bending lines are arranged to divide the blank into three sections, namely, the cover 4, the back 5 and the locking section 6. In the embodiments shown in the drawing, the sections are of substantially equal length, although the dimensions may be varied as desired.

Referring now particularly to Figure 7 of the drawing, the locking section 6 is provided with a rectangular opening 7 of substantial length. The width of the opening is preferably substantially equal to the width of the wrapped razor blades 8 in order to prevent lateral movement and possible displacement of the latter when inserted in the packet. As shown in the drawing, the opening 7 is formed by cutting a U-shaped slit 9 in the locking section 6, the spaced ends of the slit extending toward the free end of said section. The central tab 10 formed by the slit 9 may then be bent along the dotted line 11 obliquely of the plane of the locking section to form the opening 7. As shown in Figures 7 and 8, the tabs 10 have been bent obliquely away from the plane of the section 6 so as to expose the openings 7 to view. Alternatively, the tab 10 may be removed from the section 6 by severing it along the dotted line 11. It is preferred that the tab 10 remain, however, for purposes explained in detail hereinafter.

35 A portion of the cover section 4 adjacent its free end is reduced in width to form a tongue 12 proportioned and arranged to be received removably in the opening 7 when the packet is closed. It is to be noted that the length of tongue 12 is substantially equal to the distance between the score line 3 and the adjacent edge of opening 7. This distance is preferably made as great as is practicable for the article to be packaged in order that a long tongue may be provided to insure against accidental opening of the packet. In the embodiments illustrated, this distance is slightly less than one-half the length of the razor blades 8.

40 A transverse slot 13 may also be provided in the cover for cooperative registration with the tab 10. As shown in Figure 6 of the drawing, the end of tab 10 may be inserted in the slot 13 for abutment with the underlying back 5. In this position the tab is secured against displacement and 45 functions as a brace for supporting the locking

section 6 in an inclined position for displaying the razor blades. Alternatively, substantially the entire tab 10 may be inserted through slot 13, as shown in Figure 5. In this position the tab lies between the back 5 and cover 4 and functions to secure the locking section 6 releasably to the cover 4.

Holes 14 are provided in each of the sections 4, 5 and 6 for cooperative registration when the packet is folded to either of the positions best shown in Figures 1 and 4. In this manner the packet may be supported upon a peg 15 in either closed or open arrangement, as described in detail hereinafter.

In Figure 8 there is shown a packet which provides a plurality of openings for packaging greater quantities of razor blades or other articles. Each opening 7 is provided with its corresponding tab 10, tongue 12 and slot 13 as described hereinbefore. Thus, as many pockets as desired may be provided in a single blank by substantial duplication of the construction previously described.

The packet is employed in packaging razor blades as follows: The blank is folded along the dotted lines 1, 2 and 3 in such manner that the locking section 6 and cover 4 are caused to overlap. A quantity of wrapped razor blades, for example five in number, is inserted in the opening 7, the inserted ends of the blades abutting against the edge of the packet defined between fold lines 2 and 3. The tab 10, if provided, underlies the razor blades adjacent the back section 5. The cover 4 is then folded over the locking section 6, and tongue 12 is inserted through opening 7 between the first razor blade and the locking section. The filled packet is now ready for shipment.

Referring particularly to Figures 3, 5 and 6 of the drawing, it is to be noted that the sides of the locking section 6 adjacent the lateral edges of the opening 7 curve smoothly across the lateral edges of the blades 8 from the edge 9 of the opening adjacent the line 3 to the dotted line 11. The blades are thus secured for a substantial distance along their edges, and thereby are prevented from becoming displaced in the packet during transport and other normal manipulations. This provision of an opening 7 of substantial length is an important feature of the present invention.

The razor blades may be displayed, for example, upon a merchandise counter either in the closed packet or by opening the packet as follows: The tongue 12 is withdrawn from the opening 7 and the cover 4 bent back. The locking section 6 is then raised from its position against the back 5, and the cover 4 folded down against the back. The tab 10 is then bent at a substantially right angle to the plane of the locking section 6 and the free end of the former is inserted in the slot 13 provided in the cover 4, as illustrated in Figure 6. In this position the razor blades extend outwardly from the inclined locking section 6 for attractive display.

The blades may also be displayed for convenient access in the home, as follows: Upon purchasing a packet of the blades, the cover 4 is bent back, the locking section 6 raised, and the cover placed against the back 5. The locking section is then folded against the cover with the blades exposed to view. The opened packet may then be supported upon a peg 15 provided at the desired location by hanging the packet from the registering holes 14. Alternatively, the tongue 12

may be inserted through the slot 13 to the position shown in Figure 5, whereby to lock the locking section 6 and cover 4 together. It is apparent that by this latter arrangement the locking section 6 need not be as long as illustrated and that the hole 14 provided in the locking section may be omitted. The open packet may be supported upon a peg by the registering holes 14 provided in the cover and back sections.

From the foregoing description it is apparent that the present invention provides for the novel packaging of razor blades for shipment and display. The packet is of simplified and therefore economical construction. It provides for the packaging of one or more individually wrapped blades and facilitates the removal of the blades when desired. The packaging of the blades for shipment is also simplified, since all that is required is the insertion of a desired number of blades in the opening 7.

It will be apparent to those skilled in the art that various other articles of manufacture may be packaged in the packet of this invention. For example, needles may be secured to flat cards in the usual manner and a plurality of the cards inserted in the opening 7 of the locking section 6. Similarly, hair pins may be arranged upon cards which are receivable in the opening 7. Sticks of chewing gum, flat cosmetic bottles and many other articles may also be packaged in this manner. In any case it is necessary only to proportion the packet properly to accommodate the article to be packaged.

It will also be apparent to those skilled in the art that various details of the structure described hereinbefore may be modified without departing from the scope and spirit of this invention. Accordingly, it is to be understood that the foregoing description is merely illustrative of the invention and is not to be considered in a limiting sense.

Having now described my invention and the manner in which the same may be used, what I claim as new and desire to secure by Letters Patent is:

1. A packet for packaging articles of manufacture, comprising, in combination with an article to be packaged, a blank of sheet material adapted to be folded transversely to form a back section and an overlying locking section, the locking section having an intermediate opening therein for receiving a portion only of said article therethrough, a tab projecting from the locking section, a cover section connected to the end of the back section opposite the locking section, the cover section being adapted to be folded in between the back and locking sections, the cover section having a transverse slit therein arranged to receive the said tab therethrough, whereby the free end of the tab may be stabilized in contact with the back section to form of said tab a brace supporting the locking section in angular position with respect to the back section for displaying the said article.

2. A packet for packaging articles of manufacture, comprising, in combination with an article to be packaged, a blank of sheet material adapted to be folded transversely to form a back section and an overlying locking section, the locking section having an intermediate opening therein for receiving a portion only of said article therethrough, a tab projecting from the locking section, a cover section connected to the end of the back section opposite the locking section, the cover section being adapted to be folded

in between the back and locking sections, the cover section having a transverse slit therein arranged to receive the said tab therethrough, whereby the tab may be reeved through said slit and disposed between the back and cover sections to secure the three packet sections together in substantially parallel planes for displaying the said article.

3. A packet for packaging articles of manufacture, comprising, in combination with an article to be packaged, a blank of sheet material adapted to be folded transversely to form a back section and an overlying locking section, the locking section having an intermediate opening therein for receiving a portion only of said article therethrough, a tab projecting from the locking section, a cover section connected to the end of the back section opposite the locking section, the cover section being adapted to be folded in between the back and locking sections, the cover section having a transverse slit therein arranged to receive the said tab therethrough, whereby the free end of the tab may be stabilized in contact with the back section to form of said tab a brace supporting the locking section in angular position with respect to the back section for displaying the said article and whereby the tab may be reeved through said slit and disposed between the back and cover sections to secure the three packet sections together in substantially parallel planes for displaying the said article.

4. The packet of claim 3 wherein the opening in the locking section and the tab projecting from the locking section are formed by a U-shaped slit in the locking section, the tab projecting from the transverse edge of the opening adjacent the free end of the locking section.

5. A packet for packaging articles of manufacture, comprising, in combination with an article to be packaged, a blank of sheet material adapted to be folded transversely to form a back section and an overlying locking section, the locking section having an intermediate opening

therein for receiving a portion only of said article therethrough, a tab projecting from the locking section, a cover section connected to the end of the back section opposite the locking section, the cover section being adapted to be folded over the locking section, and a tongue on the cover section arranged for removable insertion in the opening of the locking section over the article contained therein for releasably securing the packet sections together in closed condition, the cover section also being adapted to be folded in between the back and locking sections, the cover section having a transverse slit therein arranged to receive the said tab therethrough, whereby the free end of the tab may be stabilized in contact with the back section to form of said tab a brace supporting the locking section in angular position with respect to the back section for displaying the said article and whereby the tab may be reeved through said slit and disposed between the back and cover sections to secure the three packet sections together in substantially parallel planes for displaying the said article.
